CHESTER A. CRISLIP, OF SPENCER, WEST VIRGINIA.

HASP-LOCK.

1,315,883.

Specification of Letters Patent.

Patented Sept. 9, 1919.

Application filed May 18, 1917. Serial No. 169,467.

To all whom it may concern:

Be it known that I, JAMES V. THOMPSON, a citizen of the United States, residing at Spencer, in the county of Roane and State 5 of West Virginia, have invented new and useful Improvements in Hasp-Locks, of which the following is a specification.

The present invention has reference to hasps generally, and comprehends particularly 10 improvements in hasp locks.

This invention is directed more specifically to a hasp lock structure and is designed primarily as an improvement upon Patent 1,057,899, issued to me April 1, 1913.

15 The primary object of the present invention resides in the provision of a novel construction of locking means which will securely fasten the hasp lock against movement and is manipulated to a released position through the medium of a key, consequently preventing any unauthorized person from gaining entrance to the structure 20 or dwelling to which the hasp lock is connected without possessing the proper key.

25 A still further object of the present invention is the provision of a hasp lock, which is extremely simple in construction, durable, reliable and efficient in its purpose, inexpensive to manufacture, and wherein the 30 pivot bolt is provided with a squared shank for holding the same against rotary movement with respect to the hasp.

With the above and other objects in view, the invention consists in the novel features, 35 details of construction and combination of parts which will hereinafter be more fully set forth, illustrated in the accompanying drawing and pointed out in the appended claim.

40 Figure 1 is a side elevation of a hasp lock constructed in accordance with the invention;

Fig. 2 is a view of the hasp with the hasp lock removed therefrom;

45 Fig. 3 is a side elevation of the hasp hook with a portion thereof shown in section, to clearly illustrate the locking means; and

Fig. 4 is a perspective view of the pivot bolt.

50 Referring more particularly to the accompanying drawing, in which like characters of reference refer to corresponding parts in the several views, the hasp is denoted by the character 5 having formed in

its inner end an eye 6 through which is passed a staple 7 for stationarily mounting the hasp in a door or door frame, as is obvious. In the opposite end of the hasp I provide an elongated slot 8 for the detachable engagement thereof with a second staple forming a keeper 9, which, in event of the staple 7 being secured to the door, is fastened to the door frame in the ordinary well-known manner.

The chief characteristic of this invention, 65 aside from the improved type of locking means, to be hereinafter referred to, use is made of a novel type of pivot bolt denoted by the character 10, for swingingly supporting upon the hasp 5 a hasp hook 11 provided 70 with a doubled hooked end 12 adapted for engagement in the keeper 9. To this end, the pivot bolt embodies a circular head 13 and a shank 14, the shank for a portion of its length being substantially of circular 75 form in cross section, while the remaining portion of the shank and to the free end thereof is rectangular in cross section, denoted by the character 15, and adapted to be projected through the squared opening 16 of the hasp for holding the locking bolt to 80 the hasp against any accidental rotation. The circular portion of the shank is indicated by the character 17 and has formed in its outer periphery a recess 18, the purpose of which will be hereinafter more fully set forth as the description of the invention 85 is proceeded with.

The pivot end of the hasp hook is provided on the inner face thereof with a socket 90 19 of substantially circular form and encircling the opening 20 through which the pivot bolt 10 is projected for swingingly supporting the hasp hook to the hasp. The locking member indicated by the character 95 21 is here shown as constituting a dog pivoted as at 22 in the socket 19 and the spur end 23 of the dog is automatically thrown into locked engagement with the recess 18 of the portion 17 of said pivot bolt through the medium of a V-shaped leaf spring 24 secured adjacent the shoulder 25 as at 26. Obviously, from Fig. 3 of the drawing, the pivot denoted by the character 22, is projected 100 through the lower end of the locking member 21 and positioned axially or in spaced parallelism with the circular shank 14 of the pivot bolt, and by the provision of the con-

caved face 28 of the pivot being disposed in confronting relation with the shank 14, not only facilitates the expeditious operation of the pivoted locking member, but will further facilitate the locking member in conforming with the contour of the shank 14 of the pivot bolt.

Provided in the head 13 of the pivot bolt is a key-hole 27 in which a suitable key, not shown, is adapted to be inserted for releasing the pronged end 23 of the locking dog from the pivot bolt, and thereby moving the bolt out of engagement with the notch 18 so that the said hasp hook can be swung in a direction for freeing or releasing the hasp.

From the foregoing description, taken in connection with the accompanying drawing, the advantages of construction and the method of operation will be readily apparent to those skilled in the art to which the invention relates, and while I have described the principles of operation of the invention, together with the device which I now consider to be the best embodiment thereof, I desire to have it understood that the device shown is merely illustrative, and that such changes may be made when desired as are within the scope of the appended claim.

What is claimed as new is:—

The combination with a hasp provided with a squared opening, of a headed pivot bolt having a squared end adapted to be projected in the squared opening of the hasp for non-rotatably connecting the pivot with said hasp, said pivot bolt at a point between the head and squared end thereof being formed with a shank of circular form in cross section provided in the outer periphery thereof with a notch of right angular formation, a hasp hook provided in its inner end with a circular opening through which the shank of the pivot bolt projects and a portion of the wall of the opening being cut out to provide a socket, a spring pressed locking member mounted in the socket, a pivot passing through the lower end of the locking member and arranged axially of the shank of the pivot, the inner face of the locking member being concaved to conform to the contour of the shank of the pivot bolt and adapted to be retracted by a key, the formation of said notch permitting the key to stop in alignment with the insertion point of the latter.

In testimony whereof I affix my signature. 55
JAMES V. THOMPSON.
